COMBINED SLIDE AND STRIP FILM PROJECTOR, SOUND AMPLIFIER, AND CARRYING CASE THEREFOR

Ben Greene, New York, N. Y.

Application May 24, 1952, Serial No. 19,877

Term of patent 7 years

(Cl. D61—1)

To all whom it may concern:

Be it known that I, Ben Greene, a citizen of the United States of America, residing in New York city, county of New York, and State of New York, have invented a new, original, and ornamental Design for a Combined Slide and Strip Film Projector, Sound Amplifier, and Carrying Case Therefor, of which the following is a specification, reference being had to the accompanying drawing, forming part thereof.

Fig. 1 is a perspective view of a combined slide and strip film projector, sound amplifier, and carrying case therefor in a closed position, showing my new design;

Fig. 2 is another perspective view of Fig. 1;

Fig. 3 is Fig. 1 in an open position;

Fig. 4 is a perspective view of the top with the screen partially open; and

Fig. 5 is a fragmentary perspective of the drawer portion with the projector in upright position.

I claim:

The ornamental design for a combined slide and strip film projector, sound amplifier and carrying case therefor, substantially as shown.

BEN GREENE.
